CLOTHES HAMPER

Elizabeth W. Seymour, Canton, Ohio

Application July 19, 1951, Serial No. 237,584

2 Claims. (Cl. 312—297)

1

The invention relates to clothes hampers, and more particularly to a hamper having a removable, preferably, fabric bag insert to facilitate the storage and handling of soiled clothes.

Usual types of clothes hampers having a box-like structure with a top opening lid must either be picked up and turned up side down to empty the hamper, or the housewife must reach into and ultimately to the bottom of the hamper and remove the clothes piece by piece. This involves bending or stooping and reaching to the bottom of the hamper to remove the clothes, which is difficult and tiring for a woman. Sometimes in depositing or removing soiled clothes in or from the usual clothes hamper, the clothes and particularly fragile articles may be snagged or torn on an internally projecting part of the hamper.

In order to overcome these difficulties and to provide other advantages, I have combined with a modified conventional hamper element a top opening cloth bag container suspended at the top of two of its side walls on a collapsible frame which may be inserted into and removed from the hamper element. The hamper and frame are formed with interengaging means by which the bag may be supported at an upper level at the upper end of and above the hamper element to provide convenient access to the bag for the removal of soiled clothes therefrom without bending or stooping or reaching to the bottom of the hamper element.

Accordingly, it is a general object of the present invention to provide an improved clothes hamper construction which may be emptied without stooping, bending or reaching to the bottom of the hamper element when resting on the floor.

Furthermore, it is an object of the present invention to provide a new clothes hamper construction including a removable cloth bag suspended on a collapsible frame which may be supported at the top of the hamper element when the latter is resting on the floor to facilitate the easy and tireless removal and sorting of soiled clothes from the bag.

Also, it is an object of the present invention to provide a new clothes hamper construction including a removable cloth bag element suspended on a collapsible frame which may be removed from the hamper element and moved from place to place in collecting soiled clothes, and which bag element likewise may be removed from the hamper element when filled with soiled clothes and carried to the laundry in the basement or

other locations in the home in connection with laundering the soiled clothes.

Furthermore, it is an object of the present invention to provide a new clothes hamper construction including a removable cloth bag element which may be removed from the hamper element when filled with soiled clothes and utilized as a laundry bag for shipment to a commercial laundry.

Finally, it is an object of the present invention to provide a new clothes hamper construction including a removable cloth bag element which permits adequate ventilation of the hamper parts, which is light in weight, which has substantially the same capacity as the capacity of the hamper element, which may be manufactured inexpensively, and which, when associated with a hamper element, overcomes difficulties, solves existing problems in the art, and has the described characteristics and advantages.

These and other objects and advantages, apparent to those skilled in the art from the following description and claims, may be obtained, the stated results achieved, and the described difficulties overcome by the construction, combinations, sub-combinations, arrangements, devices, elements and parts which comprise the present invention, the nature of which is set forth in the following general statement, a preferred embodiment of which—illustrative of the best mode in which applicant has contemplated applying the principles—is set forth in the following description and shown in the drawings, and which are distinctly and particularly pointed out and set forth in the appended claims forming a part hereof.

The nature of the discoveries and improvements of the present invention may be stated in general terms as including in clothes hamper construction, a box-like hamper element preferably having a top opening lid, a fabric bag shaped to be received within and to conform closely to the interior of the hamper element, a collapsible preferably pivoted X-frame support member adapted for insertion within the hamper element, means for suspending the top of the bag from the top of the frame, and cooperating means on the lower end of the frame and at the upper end of the hamper element adapted to support the frame with the bag suspended therefrom at and above the top of the hamper element.

By way of example, a preferred embodiment of the improved clothes hamper construction is

illustrated in the accompanying drawing forming a part hereof wherein:

Figure 1 is a front vertical sectional view of a clothes hamper construction incorporating the improvements of the present invention;

Fig. 2 is a side vertical sectional view of the hamper shown in Fig. 1;

Fig. 3 is a view similar to Fig. 1 illustrating the cloth bag element supported by the collapsible frame at the top of the hamper element; and

Fig. 4 is a perspective view of the cloth bag element and collapsible frame therefor removed from the hamper element.

Similar numerals refer to similar parts throughout the various figures of the drawing.

In accordance with the present invention a usual type of clothes hamper is utilized which may be made of wood, metal, wood and wicker, or metal and wicker. In the drawing a conventional wood and wicker hamper element is generally indicated at 1 having feet 2 which rest on the floor and the top of the hamper may be provided with a hinged lid 3. This conventional hamper is modified in accordance with the present invention by mounting cleats, rests or projections 4 on the hamper element side walls adjacent the top ends thereof for a purpose to be later described.

A cloth bag element generally indicated at 5 is located within the hamper element 1 conforming generally to the internal configuration of the hamper 1. The bag 5 is supported on a collapsible X-frame generally indicated at 6, the frame preferably comprising rectangular frame members 7 centrally pivoted at 8 thus forming a pivoted X-frame having lower cross members 9 and upper cross members 10. The cross members 10 may be formed inward to facilitate grasping the frame when removing the same from the hamper.

The X-frame 6, as shown, may be formed of flat strip metal and welded to provide continuous frame sections, or may be similarly formed of other light weight metal section such as wire rod, metal tubes or channel bars; or it may be made in any other suitable way of any desired material such as wood strips.

The bag 5 is secured to the X-frame 6 by engaging flaps 11 over the upper frame cross members 10. The flaps 11 are preferably formed of fabric in continuation of the side walls of the bag 5 and when engaged over the cross members 10 the flaps may be secured to the side walls by snap fasteners generally indicated at 12, or by buttoning, or in any other suitable manner.

If desired, a pocket may be formed on one or more of the side walls of the fabric bag 5 by stitching a separate piece of fabric at three edges to the bag side wall, as indicated at 13 in Fig. 4.

The clothes hamper normally is located in its usual place in the home with the elements 1, 5 and 6 thereof assembled and associated in the manner shown in Fig. 1. Soiled clothes may be deposited from time to time in the bag element 5 in the usual manner merely by opening the lid 3. If desired, the X-frame 6 and the bag element 5 supported thereby may be removed from the hamper element 1 at any time by lifting upward. Thus the bag 5 supported by frame 6, each of which is light in weight, may be carried from room to room for collecting soiled clothes such as bed linen and the like.

On wash day when it is desired to remove the soiled clothes for sorting or transporting to the laundry, the upper frame cross members 10 are

grasped by the hands and the X-frame 6 and bag 5 then may be lifted to the position shown in Fig. 3, at which location, upon releasing the frame, the lower frame cross members 9 spread 5 apart and engage the hamper cleats 4 and thus support the X-frame 6 at the top of the hamper element 1 projecting upward therefrom with the bag element 5 supported thereby. In this position of the bag element 5 the soiled clothes therein 10 may be removed readily, without bending or stooping, by any person merely by reaching into the bag from a standing position.

Thus, the bag may be readily emptied without stooping and the soiled clothes may be sorted 15 as removed if desired. During such sorting step, fragile articles such as stockings, lingerie and the like may be deposited in the pocket 13; or such articles may be pre-sorted by placing them in the pocket 13 when initially depositing them in the hamper.

If more convenient for the housewife, the bag 5 may be removed from the hamper and X-frame and carried as such, filled with soiled clothes, to the home laundry for laundering the clothes.

As a further alternative, if the soiled clothes 25 are to be laundered at a commercial laundry, the snaps 12 may be released and the bag 5 removed from the X-frame 6 whereupon the snaps on one flap 11 may be engaged with the fasteners at the other side of the bag to provide the laundry bag for transporting the soiled clothes to the commercial laundry.

Since the bag and X-frame elements 5 and 6 are both very light in weight, they add little 30 weight to the weight of the clothes in lifting the X-frame 6 to the position shown in Fig. 3, or in transporting soiled clothes therein from place to place.

The X-frame 6 can be formed to fit within any 40 size of conventional clothes hamper and can be readily associated with an existing clothes hamper merely by equipping the hamper element 1 with the cleats 4.

The improved clothes hamper construction provides many advantageous features in use. The 45 hamper may be emptied without stooping or bending over or reaching to the bottom of the hamper element. This makes sorting much easier when done at the hamper. The bottom of the bag element when in raised position is within easy arm reach and is more readily visible than the bottom of the hamper element. The capacity of the conventional hamper is not reduced to any substantial degree. The cloth bag permits adequate ventilation of the soiled clothes in the hamper. The cloth bag protects clothes deposited therein from being snagged or torn on internal surfaces of the hamper element. The cloth bag can be removed from the X-frame and washed for keeping the same in a clean and sanitary condition. The frame and bag can be removed readily and placed in other rooms as a collecting receptacle. The cloth bag can be removed and used as a laundry bag to transport the clothes either to the home laundry or to a commercial laundry.

Accordingly, the present invention provides many new improvements in clothes hamper construction having the advantages and characteristics described, provides for the convenient emptying of a clothes hamper without bending or stooping or reaching to the bottom of the hamper element, avoids the possibility of injury to clothes deposited therein by snagging or tear-

ing and generally facilitates the handling of soiled clothes.

The embodiment of the present invention illustrated and described herein is by way of example, and the scope of the invention is not limited to the exact details of construction of the various parts illustrated.

Finally, in the foregoing description, certain terms have been used for brevity, clearness and understanding; and no unnecessary limitations are to be implied therefrom beyond the requirements of the prior art, because such words are used for descriptive purposes herein and not for the purpose of limitation, and are intended to be broadly construed.

Having now described the features of the invention, the construction and use of a preferred embodiment thereof, and the advantageous, new and useful results obtained thereby; the new and useful devices, arrangements, constructions, combinations, sub-combinations, elements and parts, and reasonable mechanical equivalents thereof obvious to those skilled in the art, are set forth in the appended claims.

I claim:

1. In combination, a box-like clothes hamper having an access opening in the top thereof, an X-frame including two frame members each having an upper and a lower cross member connected by parallel side members, said side members of said frame members being pivotally connected intermediate the ends thereof, a fabric bag suspended within the X-frame by side flaps thereof engaged over the upper frame cross members, said X-frame and bag removably supported within the hamper, and cleats located within the upper ends of the hamper and engageable with the

lower cross members of the X-frame to selectively support the X-frame in an elevated position in said hamper.

2. In combination, a box-like clothes hamper provided with an access opening in the top thereof, a frame member having pairs of upper and lower cross members thereon, said frame member removably supported entirely within said hamper, an open-ended fabric bag having side walls and a bottom therein, flap portions extending beyond two opposed sides of the bag at the open end thereof to engage over the upper cross members of said frame suspending said bag within said frame, cooperative detachable fasteners on said flap portions and the bag side walls engageable to secure said bag in its suspended position, a double side wall structure on one portion of said bag forming an auxiliary pocket therein, and cleats on the inner walls of said hamper adjacent the top thereof engageable with the lower cross members of the frame to selectively support said frame in an elevated position in said hamper to extend through the access opening therein.

ELIZABETH W. SEYMOUR.
